UNITED STATES PATENT OFFICE.

OLIVER P. COBB, OF AURORA, INDIANA.

PILE FOR NAIL-PLATES.

SPECIFICATION forming part of Letters Patent No. 251,834, dated January 3, 1882.

Application filed April 26, 1880. (No model.)

To all whom it may concern:

Be it known that I, OLIVER P. COBB, of the city of Aurora, in the county of Dearborn and State of Indiana, have invented certain new and useful Improvements in Piles for the Manufacture of Nail Plate and other Plate from Railroad-Rails and Wrought-Iron Scrap, of which the following is a specification.

My invention consists in a new mode of constructing the pile out of which the plate to be used in the manufacture of nails and other articles is rolled.

By the present known modes of making plate from rails and scrap the pile consisting of said rails and scrap is, after being heated in a furnace, rolled into what is known to the trade as "muck-bar." This muck-bar is then again sheared, repiled, and reheated, and then rolled into plate. My new mode of constructing the pile, which mode is more particularly hereinafter described, enables the plate to be manufactured directly from the pile at one heat—in other words, enables the manufacturer to dispense with the manufacture of the pile into muck-bar and the subsequent shearing of said muck-bar and repiling and reheating and rolling of the same. My invention enables the pile of rails and scrap, &c., made according to my improved mode to be directly placed in the heating-furnace and then carried to the plate-mill or plate-rolls, and in one operation of rolling to be made directly into plate for various purposes. My invention thus effects a saving of from twenty to thirty per cent. in the manufacture of nail-plate, as the entire manufacture is effected at one shearing, one heating, and one rolling.

Another advantage derived from the use of my invention consists in the fact that the plate manufactured from piles made according to my invention is much tougher and better than plate made from the pile as ordinarily constructed. The reasons for this advantage will be hereinafter more fully apparent.

The pile of rail and scrap as ordinarily constructed requires a hoop or binder of thin hoop-iron to hold together the various portions of the pile. This hoop or binder cools so quickly when it comes with the pile from the furnace to the air that it causes blisters upon the plate, and when nails are made from such a plate

many of them are split by imperfection of the plate, resulting from the presence of such blisters.

Another advantage from the use of my invention is that in the manufacture of nails all of the wrought-iron scraps resulting from the making of nails can be at once utilized in my improved pile.

In the accompanying drawings, making a part of this specification, Figure 1 is a perspective view of a pile made according to my invention, (with this exception, that the scrap which is placed between the rails is omitted, in order to exhibit the interstices between the latter;) and Fig. 2 is a central transverse section of the completed pile, the spaces between the rails being filled with scrap.

For the purposes of illustration I will describe my invention as applied in the manufacture of nails. The pile is usually made fifteen inches in width and about thirteen inches in length. What I designate as the "length" is the direction in which the length of the rails run when placed in the pile. The pile is made longer or shorter, according as small or large nails are to be made. The rails (usually old ones) are cut into pieces, A, of the length of the pile to be made. One edge of each lower flange of each rail is sheared off or flattened down, so as to have the edge of the flange in the same vertical plane as the edge of the top of the rail when the rail is standing as it is when in use upon a railroad-track. A piece of wrought-iron plate, B, thirteen inches long by fifteen broad is first laid down. The grain of the plate runs parallel to the length thereof. Wrought-iron scrap consisting of small flat pieces (such as have been clipped off of the ends of the nail-plates to make the latter even on the edge) is usually next placed upon the plate B. Upon this scrap three pieces, A, of rails are laid, the length of each rail being parallel to the length of the plate. Wrought-iron scrap C, however, is usually placed upon the plate B, so that when the said pieces of rails are laid thereon, the interstices between the plate B and the rails are filled with wrought-iron scrap of any suitable description. The spaces between the rails are also filled with scrap. These pieces of rail are so laid that that edge of the lower flange which has been

reduced in width shall come against the plate B. Another set of three pieces of rail is placed upon the said lower set or layer of rails, as shown, the long edge of the lower flange of 5 each piece being arranged to lie at the top side of the head of the lower pieces A, and the shorter side or edge of such lower flange therefore lying above. The interstices between the upper and lower layers are filled with wrought-
 10 iron scrap. The openings D between the upper layer of rails A and the depressions in the upper sides of the latter are filled with wrought-iron scrap. If the building of the pile and the insertion of scrap has been properly
 15 conducted, the upper surface of the pile will now be quite level, and over this pile as thus constructed is laid a wrought-iron nail-plate, E, of the same size as plate B, and the grain of the plate running parallel to the length of
 20 plate B and also parallel to the length of the plate, which in this case is thirteen inches. The pile is now completed so as to heat all parts alike without burning or blistering.

Those parts, T, of the pieces A which formed
 25 the tread when the rails were in position upon the track are usually granulated and brittle from wear and constant vibration and concussion, and the web H of the rail is, in the first instance, usually composed of poorer iron than
 30 the top and bottom portions thereof. The latter portion (the bottom) of old rails is usually very tough. It will be observed that my disposition of these rails and of the scrap with reference to each other serves to bring the brittle and tough portions of the various rails and
 35 the scrap together in such a manner that the pile, when rolled down and out into plates, shall have the same general consistency throughout. The addition of the plate B below and of the
 40 plate E above the rails serves to give the nail-plate, when rolled from the pile, a tough surface, and to give the nails made from such plate a like tough surface. The addition of the layer C of scrap also imparts additional toughness
 45 to the surface of the plate and the surface of the nail manufactured therefrom; but this layer may be omitted when it is found desirable to reduce the height of the pile. The plate E may also be omitted when desired; but I prefer to employ it, as the quality of the plate made
 50 therefrom is improved. The pile, after being

completed, is taken to the furnace and duly heated, and thence taken directly to the nail-plate mechanism and rolled out into plate.

Piles as ordinarily constructed require, as 55 before remarked, to be heated, then rolled into muck-bar, which latter is again sheared, re-handled, piled, and heated again, and then run through the nail-plate mechanism, whereby the muck-bar is formed into plate. 60

My invention saves one operation of shearing, of handling, and heating the pile in the process of making nail-plate from old rails and scrap or pig iron. For making thicker plate from the pile the number of horizontal rows 65 of pieces A in the pile may be increased, and for making wider plate the pile may be made wider by adding rails disposed in the same manner as those shown. Where more than two horizontal rows of pieces A are employed the 70 middle row or rows need not be reduced. Of course the piles may be filled in with scrap other than that made in a nail-factory, and the wrought-iron bottom and top plates may be of iron other than nail plates, and these changes 75 in the scrap and plates will naturally follow where the pile is employed to furnish plate for purposes other than the manufacture of nails.

I am aware that piles or fagots have heretofore been patented composed of rails arranged and bound in various ways, with scrap filling the interstices; also, that the flanges of such rails have been cut off to reduce their width on one side. I therefore do not claim, broadly, a 80 fagot of rails with either cut or uncut flanges, 85 but limit my claim to the particular arrangement, in a scrap-filled fagot, of rails with cut flanges.

What I claim as new and of my invention, and desire to secure by Letters Patent, is— 90

The pile or fagot constructed substantially as before set forth—namely, of horizontal rows of rails lying on their side in reverse order in the respective rows, confined between top and bottom plates, the foot or flange of each rail 95 being cut off on one side of the rail to terminate on a line with the head of the rail on that side, and the interstices being filled with scrap.
